UNITED STATES PATENT OFFICE.

FREDERICK SCHLACHTER, OF DECATUR, ILLINOIS.

LIFE-SAVING SUIT.

1,197,670.

Specification of Letters Patent. Patented Sept. 12, 1916.

Application filed April 15, 1914. Serial No. 832,029.

To all whom it may concern:

Be it known that I, FREDERICK SCHLACHTER, a subject of the Emperor of Germany, residing at Decatur, in the county of Macon 5 and State of Illinois, have invented certain new and useful Improvements in Life-Saving Suits, of which the following is a specification.

This invention relates to life saving suits 10 designed for the purpose of saving persons at sea, and one of the principal objects of the invention is to provide a flexible, rubber, water-proof suit for enveloping the entire person and providing means whereby the 15 suit may be inflated for rendering the suit sufficiently buoyant to hold up the person wearing the suit in the water, and which will be provided with a cover for the head having sight openings for the eyes and provided with valves for permitting the person 20 to breathe without admitting water.

Another object of the invention is to provide a life saving suit which will be provided with fastening devices which will prevent 25 the entrance of water to the interior of the suit and to provide means whereby the suit may be sufficiently inflated to sustain the weight of the person on the surface of the water, said suit having a head piece 30 formed integral with the body portion and provided with valves connected with the nostrils and permitting the person to breathe freely and at the same time prevent the ingress of water.

These and other objects may be attained 35 by means of the construction illustrated in the accompanying drawings, in which,

Figure 1 is a front elevation of the body portion, arm and a portion of the lower 40 part of a life saving suit made in accordance with this invention, and shown broken away above the waist, Fig. 2 is the head portion or helmet shown in front elevation, and broken away at the bottom, Fig. 3 is a view 45 in elevation of the lower portion for covering the legs and feet of the suit, Fig. 4 is a view in front elevation of the entire suit in place on a person, Fig. 5 is a detail sectional view of one of the openings and the manner 50 of rendering the opening water-proof by means of an inner bellows portion, Fig. 6 is a view of the nostril valves and connections, Fig. 7 is a detail sectional view of one of the adjustable clasp members, and Fig. 55 8 is a similar view of the other member of the clasp.

Referring to the drawings, the numeral 1 designates a life saving suit as a whole, said suit being made up of comparatively light water-proof material, like rubber cloth, and provided with an enlarged body portion 1^a, said body portion comprising inner and outer walls 2 and 3. Positioned within the body portion is an air sack designated 2', said air sack having a plurality of spaced coil springs located therein designated as 3', said springs adapted to be extended to admit air sufficient to render the device buoyant enough to support a person in water. Similar springs 3' are positioned in the sleeves of the garment, and formed on the sleeves are gloves 9. It is to be noted that the distance between the arm pit 10 and the shoulder 11 is sufficient to permit the arms to be withdrawn from the sleeve and disposed entirely within the body portion of the suit. The front portion of the suit is provided with a series of clasps for holding the parts together, the inner wall of the suit provided with hooks and eyes being generally indicated by the numeral 12 and the clasps by the numeral 13. Inside the suit where the hooks and eyes are in clasped relation there is an enlarged bellows portion 14, which may be formed integral with the air sack or as a separate piece shown in Fig. 5 which prevents the entrance of water even during the operation of connecting the eyes and clasps. The neck portion 15 may be gathered and secured around the neck by means of a tape or drawstring 16.

The air sack is provided with an inner and an outer wall and intermediate springs, and a suitable check valve is used in the air sack. The garment is placed upon the person by opening the garment at the neck and after the life saving suit has been drawn up, the neck strings 16 are brought together and tied. Owing to the action of the 100 springs, the air sack is self inflatable.

The trouser legs 17 are formed integral with the body portion of the garment and may be provided with a draw-string or tape 18 at the waist line, and by taking up the length of the legs of the trousers draw cords 19 are provided which permit an adjustment to the length of the wearer and permitting the overhanging portions 20, thus providing a suit that can be worn by persons of varying sizes without being cumbersome. Upon the inside of the leg portions

is provided a pocket 21 for food or other needed devices, while at 22 straps are provided for carrying a toilet bag 23. The head portion or hood 24 is provided with a 5 depending cape portion 25 and a draw-string 26. In the upper end of the hood 24 is a suitable nipple and check valve 27 which is normally open when the person is in an upright position. The sight openings 28 10 may either have glass or transparent celluloid disks fitted therein. The nostril valves are connected to a plate 29, and comprise the tubular portions 30, the outer ends of which are flared and provided with ball valves 31 15 which are sufficiently buoyant to seat themselves against the inner walls 32 in case water should enter the open outer ends of the valve casing 30. A wire gauze closure 33 is provided at the outer end of the casing 20 30.

The clasp for holding the front opening of the garment together comprises a female member 34 having ratchet teeth 35 and a base member 36 adapted to be secured 25 through suitable openings 37 to the garment, while the male member 38 is provided with a ratchet member 39 which engages the ratchet teeth 35 and permits adjustment inward and outward to lock the two 30 members of the clasp together. A finger hold 40 is provided for moving the male member upward or downward upon the pivotal point 41 and the base member 42 is provided with suitable openings for the fastening 35 devices for connecting it to the garment.

From the foregoing it will be obvious that a life saving suit made in accordance with this invention may be quickly applied 40 to the person and when inflated by the means of the springs 3', the person wearing the suit is entirely protected against the ingress of water, and is permitted to breathe with ease even if the water should be drawn 45 entirely over his head, or even if he should be in the water for a certain length of time. The suit can be packed within a comparatively small space when not required for use, and can be quickly put upon the person 50 when occasion requires.

The check valve at 27 will close when the person is lying flat on the water or in case of a dive.

Various changes may be made in the de-

tails of construction without departing from 55 the spirit and scope of the invention as defined in the claims.

What is claimed is:—

1. A life saving suit made of impervious material and having a neck opening of sufficient size to permit the person to enter the suit, draw-strings for the neck opening, an air sack inclosed within the suit and provided with expanding springs located within the air sack, for inflating the same, and 60 a helmet provided with a hood having gathering strings connected to the neck portion, and provided with valves for the nostrils and sight openings for the eyes.

2. A life saving suit adapted to envelop 70 the entire body and made of a single piece provided with a neck opening and draw-strings, a helmet having a depending cape provided with draw-strings for engagement around the neck, said helmet having nostril 75 valves comprising tubular portions, ball valves and seats therefor at the outer end of said tubular portions, draw-strings for the waist line, draw-strings for the trouser portions at the knee, an inflatable air sack, 80 springs located between the inner and outer walls of said sack, and fastenings for the front portion of the body of the garment.

3. A life saving suit comprising an integral body portion, arm and leg portions 85 and an enlarged neck opening, said arm portions permitting the removal of the arms of the wearer therefrom, an air sack within the suit, springs located within said sack, said springs rendering the same self-inflatable, and a detachable helmet provided with a cape and draw strings for forming a water tight connection between the neck of the garment and the cape of the helmet.

4. A life saving suit including an air 95 sack, springs located in the sack to render the same self-inflatable.

5. A life saving suit comprising inner and outer walls, an air sack located between said walls, springs positioned between the walls 100 of the air sack for rendering the same self-inflatable.

In testimony whereof I affix my signature in presence of two witnesses.

FREDERICK SCHLACITER.
